UNITED STATES PATENT OFFICE.

GEORGE W. NISTLE, OF NORTH MUSKEGON, MICHIGAN, AND EDWARD INSKIP AND BERNARD W. BRADY, OF CHICAGO, ILLINOIS.

BLOCK SYSTEM FOR RAILWAYS.

No. 926,818.

Specification of Letters Patent.

Patented July 6, 1909.

Application filed November 18, 1907. Serial No. 402,610.

To all whom it may concern:

Be it known that we, GEORGE W. NISTLE, residing at North Muskegon, in the county of Muskegon and State of Michigan, and EDWARD INSKIP and BERNARD W. BRADY, residing at Chicago, in the county of Cook and State of Illinois, citizens of the United States, have invented certain new and useful Improvements in Block Systems for Railways, 10 of which the following is a specification.

This invention relates to improvements in block systems, and refers more particularly to improvements in a system of that general type in which mechanism located along the 15 track coöperates with mechanism upon the train to automatically arrest the latter in case the train be sent into a block, the block mechanism of which is set at danger.

The salient object of the present invention 20 is to provide a system which is completely automatic in its arresting functions and of reliable construction and operation, thereby eliminating the "personal equation" to the greatest practicable extent and reducing the 25 danger factor to a minimum.

Other objects of the invention are to provide simple and effective mechanism for co-operating with the air brake system with which nearly all trains are now equipped and 30 whereby said air brake mechanism is brought into operation automatically in case the block conditions are such that this should be done; to provide an improved type of track lever which constitutes an important factor 35 in simplifying such systems and specifically so in carrying out the system herein described; to provide a system so organized that it is not functionally disarranged or disordered in case a train or car should be made 40 to traverse the track backwardly; to provide in conjunction with the automatic arresting mechanism, coöperative signaling mechanism; and in general to provide an improved system of the character referred to.

45 The invention consists in the matters hereinafter described, and more particularly pointed out in the appended claims.

In the accompanying drawings—Figure 1 shows diagrammatically an embodiment of 50 the system as applied to one track only of a double track railway; Fig. 2 is a detail in side elevation of one of the track instruments, parts being broken out to reduce the size of the figure; Fig. 3 is a cross sectional view

taken on line 4—4 of Fig. 2 and looking in 55 the direction of the arrows; Fig. 4 is a detail in side elevation of the controlling wheel and associated parts and their mountings; Figs. 5, 6 and 7 are detail side elevations of the different track instruments which coöperate 60 with the controlling wheel; Figs. 8 and 9 are cross sectional details taken on the lines 8—8 and 9—9, respectively, of Figs. 5 and 6; Fig. 10 is a front end elevation of the track instrument shown in Fig. 6. 65

In carrying the present invention into effect, we employ a novel type of circuit controlling track instrument, each of which instruments has as its main feature a lever carrying contact making devices, pivoted between its ends and provided with two or more tread surfaces inclined relatively to each other so that as the lever is traversed by a wheel it will be oscillated and left in one position or another, depending upon the direction of traverse of the wheel and direction of inclination of said tread surfaces. Sets of these track instruments, varying somewhat in construction but all of the same general type, are located along the rails of the 80 railroad in position to be encountered by a controlling wheel carried in some suitable manner by some part of the train, and this controlling wheel is, under certain conditions, raised or forced upwardly by the track instruments, and thereby cause to vent the train pipe of the automatic air brake mechanism of the train, and thus bring about the 85 arresting of the latter.

In the diagram, A designates as a whole 90 the railroad track, T a train, and these shown diagrammatically, and C, D, D' and E track instruments, which together constitute an operative set.

Inasmuch as the several track instruments 95 are differently constructed, and these differences involve somewhat different operations, the construction of said instruments will first be described.

Referring to Fig. 2, the instrument there 100 shown is that designated C. This instrument comprises a suitable base plate 15 adapted to be secured to a cross tie or other suitable support upon the roadbed, and constitutes a pivot support for the main lever of 105 the instrument 16, being to this end provided with a standard portion 17 to which the lever is pivoted as indicated at 18. The

lever 16 is desirably made of angle iron, so as to be both light and strong, and it is bent to provide oppositely downwardly inclined top tread surfaces 19, 19', at its end, and downwardly inclined converging intermediate tread portions 20, 20'. The lever is so supported, relatively to the line of travel of the controller wheel which actuates the lever, that it will be oscillated by the traverse of the wheel thereover. This lever may stand in either of its two positions when encountered by the controller wheel, *i. e.* with its rear end elevated or with its forward end elevated. In the latter instance the controller wheel will simply depress the forward end, while in the former case if the rear end be elevated the controller wheel will first depress the rear end and thereafter depress the forward end, assuming, of course, that the wheel traverses it in the usual forward direction.

The position of the lever is positively controlled by either one of two magnets M and M' and coöperating latch mechanisms, and in addition to the magnet control the rear end of the lever is weighted, as indicated at 21, so that the lever will return to a normal position by gravity when not held by one or the other of the latches.

Describing said latch mechanisms, both being alike, and referring to Fig. 3, upon the side of the lever 16 toward the magnet M or M' is mounted a latch block 22 having a shoulder 23 with which is adapted to coöperate a latch 24 pivoted at its lower end, as indicated at 25, and carrying an armature 26 which is acted upon by the magnet. A spring 27 interposed between the latch and the head of the magnet spool tends to press the latch away from the magnet and into engagement with the latch block 22.

The two latch mechanisms are similarly disposed, and each tends to hold its own end of the lever locked positively in uplifted position, but when one end of the lever is latched up the opposite end is, of course, depressed below the latching position.

In Fig. 5 is shown the instrument designated D' in the diagram. The general construction and shape of this lever is, or may be, precisely the same as that of the instrument C. It is similarly mounted on the base 15 and weighted at its rear end, as indicated at 21, so as to tend to return it to a normal position. This instrument is employed for momentarily closing a circuit while the controller wheel is passing over its lever 28. To this end the forward end of the lever carries a contact plate 29, insulated from the body of the lever and adapted to coöperate with a pair of plates 30 mounted upon a suitable fixed support 31 below the lever; the relative arrangement of these parts being shown clearly in Figs. 5 and 8.

In Fig. 6 is shown the instrument design-

nated D in the diagram. The lever 32 of this instrument is, or may be, of the same shape and construction as that of the instrument D', and said lever is similarly mounted upon a suitable base 33. The lever 32 is provided at its rear end with an insulated contact plate 34 adapted to coöperate with a pair of stationary plates 35 mounted upon the base frame 33, while the forward end of the lever is provided with two insulated contact plates (see Fig. 10) 36 and 37, adapted to coöperate with corresponding pairs of stationary plates 38 and 39, respectively, also mounted on the base frame 33, as seen clearly in Figs. 6 and 10.

The lever D is provided with a friction latch mechanism adapted to hold the lever yieldingly in either of its two positions in which it happens to be left. This friction latch mechanism comprises a magnet m arranged to act upon a pivoted latch member 40 carrying an armature 41 and provided with a conical or double inclined engaging end 42 which coöperates with correspondingly shaped recesses, as 43 and 44, formed in the side face of the lever and at suitable points corresponding to the two positions of the lever. The latch is held normally in engagement with the lever by means of an expansion spring 45 interposed between the latch and head of the magnet spool.

In Fig. 7 is shown the instrument E. This instrument is in construction generally similar to the instrument D just described, having a similarly shaped lever 46 supported on a suitable base 47, but carrying at its front end a single contact plate 48 only. This plate coöperates with a pair of stationary plates 49 mounted upon the base. This instrument is also controlled by a friction latch, but said latch in the preferred construction shown consists simply of a spring arm 50 having its lower end rigidly mounted upon the base frame 47 and provided at its upper end with a conical engaging point similar to the point 42 of the instrument D and similarly adapted to coöperate with recesses 51 and 52 in the side of the lever. Inasmuch as this instrument is to be shifted positively from one position to the other, it is unnecessary to provide means for withdrawing its friction latch so as to permit it to return by gravity.

Next describing the controller wheel and its associated mechanism, and referring to Fig. 4, upon a suitable part of the train, as for example upon the journal box of one of the axles of the tender, is mounted a frame designated as a whole 53, and which in turn carries a lever 54 pivotally mounted between its ends, as indicated at 55. A pipe 56 connected with, and leading from, the air train-pipe of the train, extends through a suitable block or support 57 upon the frame 53 and terminates in a cap 58 which is nor-

5 mally held upon the pipe so as to close and seal the latter by means of an upright lever 59 pivoted upon the frame, as indicated at 60. This lever is held in position to retain the cap 58 by an extension 61 of the lever 54; the arrangement being such that when this end of the lever is depressed it releases the lever 59 and vents the train-pipe. Upon the longer end of the lever 54 is mounted 10 the controller wheel 62, which coöperates with the several levers of the track instrument hereinbefore described. This controller wheel is provided with a relatively wide tread of sufficient width to simultaneously engage two of the levers of the track instrument which are sometimes arranged in overlapped relation to each other, as will herein- 15 after appear, and the wheel is held against rising until it encounters a lever which is held positively in fixed position by a relatively stiff spring 63 mounted upon the frame 53 and bearing upon the upper side of the lever 54. When the controller wheel has been lifted so as to release the lever 59, 20 vent the train-pipe and so apply the brakes and arrest the train, the parts associated with the controller wheel will be restored to their normal positions manually by the trainmen.

25 30 The circuits of the system which utilizes the mechanism just described will now be traced.

Referring to diagrammatic Fig. 1 the system is therein shown as organized for controlling a single way track, *i. e.*, a track over which the trains normally pass in one direction only, as is usual where double tracks are employed. It is to be observed that the several contact levers at the left-hand end of 35 the first block occupy the positions (diagrammatically) which correspond to the train having fully entered said block in passing from left to right.

40 The several levers and their magnets are 45 designated by the same numerals used in describing these mechanisms.

At each end of the block are arranged four levers D', C, D, and E and also a circuit controlling lever E', one only being shown in the 50 diagram. The levers C serve as blocking levers and are respectively controlled by the magnets M and M' at either end thereof. The arrangement is such that either end of 55 one of these levers C may be set in blocking or danger position to prevent the passage of the train, by the deenergization of the magnets M and M' as heretofore described. These magnets are normally energized, *i. e.*, when the block is in cleared position.

60 65 Describing now the circuits which control the magnets M and referring to the one at the forward end of the block, the circuit connections being duplicated for the magnet M at the rear, a normally closed circuit which controls this forward magnet M extends from

line L by way of conductors 64 through the windings of the forward magnet M to conductor 69 thence by way of branch conductor 70 to the rear contacts of the rear lever D, thence by conductors 71 to the contacts of 70 the lever E' at the forward end of the block to ground at 73 by way of conductor 72. Inasmuch as the rear end of the lever D and the forward end of lever E' are normally depressed so as to close their contacts, the magnet M is obviously normally energized. It will thus be seen that the opening of the rear contacts of either lever D or the contacts of lever E' by the passage of the controller wheel, will deenergize the magnet M and 80 place the rear end of the lever C in blocking position.

In order that the magnets M may be energized independently of the action of the levers D and E', we provide another controlling circuit as follows: from line L to conductor 64 through the windings of magnet M as heretofore described thence to a branch conductor 65 to the contacts of the lever D' to ground at 67 by way of conductor 66. This circuit is normally open through the contacts of the lever D' which it will be remembered has its rear end depressed by gravity.

It is to be noted that the rear end of lever 95 C overlaps the forward end of the instrument D', so that while the front end of the latter is depressed by the controller wheel and the magnet M thus energized and its latch withdrawn, the controller wheel may 100 engage and depress the rear end of the lever C in the event the latter does not already occupy this position.

Describing now the circuits which energize the magnets M' and referring to the one at the rear of the block, it being noted that the circuit connections for the forward magnet M' are exactly similar, the circuit which controls the rear magnet M' may be traced as follows: from line L to conductor 68 through 105 the windings of magnet M', thence by way of branch conductor 70 to rear contacts of the adjacent lever D, from these contacts to conductor 71 to the forward end of the block, to the contacts of lever E' and thence to 110 ground at 73 by way of conductor 72. Inasmuch as the rear end of the levers D and the forward end of the levers E' are normally depressed the magnets M' are obviously normally energized and their respective latches 115 withdrawn. The lever E' and the ground 73 of the circuit which controls the forward magnet M' are not shown in the diagram but are arranged in exactly the same manner as just described.

125 It might be here noted that the magnets M' may also be energized by placing on the ground 67, but inasmuch as these circuits are only momentarily closed, *i. e.* during the time the controller wheel is passing over one 130

of the levers D', and inasmuch as they perform no electrical function in the system, they need not be described in detail.

The levers D are controlled by the magnets m and their corresponding latch mechanisms. It will be remembered that in case the forward end of one of the levers D was depressed it was held in that position by means of the friction latch mechanism 40 10 (see Fig. 9) and there held until its magnet m was energized and the latch withdrawn.

Describing now the circuit connections which control these respective magnets m and tracing the circuit connections of the 15 rear magnet m, the circuit extends from line L by way of conductor 74 through the windings of the magnet m to conductor 75 to the forward end of the block thence to the contacts of lever E to the conductor 76, from 20 conductor 76 to one set of the contacts on the front end of the forward lever D to conductor 77 thence by way of conductor 71 to the contacts of lever E' and ground 73 in the block ahead. This circuit is normally open through 25 the forward contacts of lever D in the advance end of the block, inasmuch as in the normal position of this lever its rear end is depressed and the forward end elevated. It will thus be seen that as the conductor wheel 30 rises over either end of the levers D the latch mechanism will hold the forward end of the lever in depressed position inasmuch as the controlling magnet m will be deenergized. However, when the train passes out of the 35 block it will depress the forward end of lever D at the forward end of the block which will close the circuit just traced thus energizing the magnet m at the rear, withdrawing its latch mechanism and permitting the rear 40 lever D to return to normal position. This clears the block as will hereinafter more clearly appear.

The levers E and E' are adapted for use in case a train is backing through the block and 45 their respective functions will be more fully described hereafter.

Assuming that a train is passing forwardly through the block and has fully entered the same as shown in the diagram, the operation 50 of the system is as follows; when the train was entering the block its controller wheel first encountered and depressed the forward end of the lever D' thus closed the circuit which energized the rear magnet M and with- 55 drew the latch and permitted the controller wheel to ride over the rear end of the lever C. Inasmuch as at this time the rear magnet M' was energized and its latch withdrawn, the controller wheel could oscillate the forward 60 end of the lever C and safely pass over this lever. When the controller wheel reached the rear lever D it found its forward end elevated and depressed the same as it passed thereover. The lever D however after the 65 passage of the controller wheel did not re-

turn to its normal position because of its friction latch mechanism, the magnet m being deenergized as heretofore described.

The train now having passed safely into the block is protected from a train advancing 70 from the rear. This resulted from the fact that when the controller wheel of the train passed over the rear lever D it depressed the forward end of said lever and latched it in that position. This opened the contacts at 75 the rear end of this lever cutting off the ground E' through and deenergizing the rear magnet M'. The latch mechanism of this latter magnet was now released and the blocking lever C placed in danger position. 80

As the train proceeded into the block the controller wheel passed over the rear lever E and oscillated the same without however performing any electrical function inasmuch as it restored this lever to the position in which 85 it found it.

As the train advances in the block the controlled wheel will encounter the lever E' first elevating and then restoring the forward end of this lever to normal but without energizing 90 the rear magnet M' and clearing the block inasmuch as the ground at 73 still remains off by reason of the fact that the contacts at the rear end of the rear lever D are broken.

As the train passes out of the block in 95 question, the controller wheel will first pass over forward lever D' thus momentarily closing the second controlling circuit heretofore described which energizes the magnet M, whereupon the magnet will withdraw its 100 latch and the controller wheel can depress the rear end of forward lever C. It is necessary at this time to energize the forward magnet M inasmuch as the circuit which normally keeps this magnet energized is broken 105 at the rear contacts of the lever D at the entrance end of the block. If the block ahead is cleared, the magnet M' controlling this lever C will be energized and the controller wheel can safely pass over the forward end of this lever C. It might be here noted that as heretofore described the various magnets which control the blocking levers are normally energized when any block is in cleared position. 110

After the train passes over the forward lever C it next encounters the forward lever D and as it passes over the same depresses the forward end of the lever and elevates the rear end thereof. This closes the forward 120 contacts of this lever D, putting on the ground 73 in the block ahead and closing the circuit which energizes the rear magnet m at the entrance of the block in question. This rear magnet m thereupon withdraws its friction latch releasing the rear lever D which returns to normal position by gravity. The circuit which energizes the rear magnet M' is thereupon closed through the rear contacts of rear lever D, the latch which controls the for- 125 130

ward end of the rear lever C withdrawn and the block again in cleared position for an advancing train.

It is thus obvious that the train will set 5 each block to danger or blocked position as it enters the same, and clear the block just traversed as it leaves it.

As an auxiliary feature, which may or may 10 not be employed, semaphores are arranged at the entrance to each block, each semaphore being designated S and controlled as follows: From supply - conductor L a conductor 78 leads to a contact carried by the front end of each lever D, adapted to engage when de- 15 pressed a contact connected with a conductor 79 which leads to and through a solenoid 80 and from thence to ground at 81. The solenoid when energized holds a semaphore arm S' in danger position.

20 In case a train desires to back into a block the system is so arranged that the blocking levers C at either end will be set at danger after the train has backed in thus closing the block at either end. This is true of course in 25 case the block is open when the train starts to back into the same. Assuming the block is cleared the set of levers at the forward end of the block are in their normal position, *i. e.* the position shown in Fig. 1; and the 30 levers at the other end of the block are in the same position. As a train backs into the block it will first encounter the lever E and as it passes over the latter opens the contacts at this lever. The lever remains in the position 35 it is left after the train passes over it *i. e.* with its contacts open as heretofore described. The train passing over this lever does not perform any electrical function inasmuch as the contacts on the front end of the forward 40 lever D are at this time open. When the train backs over the forward lever D it first closes but immediately thereafter opens the contacts of this lever and restores the same to normal position. When the traversing 45 member of the train reaches the forward end of lever C it will depress the latter inasmuch as the magnet M' controlling the latch at this end of the lever is at this time engaged. The circuit which engages this magnet extends 50 from line by way of conductor 68, windings of magnet M' branch conductor 70, rear contacts and lever D and conductor 71 to ground at 73 in the block ahead. When the traversing member encounters the rear end of this 55 lever it depresses the latter for the reason that the controlling magnet M is likewise engaged at this time and its latch withdrawn. The circuit which controls this magnet extends from line L, conductor 64, windings of 60 magnet M, conductor 69 to the rear of the block to branch conductor 70 to the rear contacts of rear lever D at this time closed, to conductor 71 to ground at 73. The train proceeding in its backward direction passes 65 over the forward lever D' which however re-

turns to normal by gravity as heretofore stated.

The train has now safely entered the block but is not protected either from a second backing train or from a train proceeding in a 70 forwardly direction. However as the train continues to back into the block its traversing member encounters the lever E' which is like the levers E, and opens the contacts at the forward end of this lever. This takes off 75 ground 73 which it will be remembered is included in the circuit of the rear magnet M' and the forward magnet M. These respective magnets are now deenergized through the opening of the contacts on this lever E' 80 and their respective latches spring into blocking position. A train now entering the block will be unable to depress the forward end of the rear lever C, while a train backing into the block will be unable to depress the rear 85 end of forward lever C. Inasmuch as the block can never be set in cleared position as long as the contacts on lever E' are open, the block remains in danger position at both ends until the train which has backed in again 90 moves forwardly and restores this lever E' to normal position.

When the train in question has passed out of the forward end of the block it automatically restores the latter to cleared position. 95 This is accomplished in exactly the same manner as heretofore described in connection with a train passing directly through the block. It being noted that as the train passes over the lever E' it closes the contacts 100 of this lever which remain in closed position.

Assuming now that a train is attempting to back into a block, when the train is in danger position *i. e.* during the time when another train is still within the block, the operation may be described as follows: When the train within the block passes over the rear lever D it opened the contacts at the rear end of this lever and set both ends of the block in danger position. This was accomplished by the fact that the rear contacts of rear lever are included in the circuit of the rear lever M' and also in the main circuit of the forward lever M as heretofore described. The forward magnet M is thus deenergized. 110 When the backing train as it enters the block will pass over the levers E and D and the forward end of lever C as heretofore described. When the traversing member however encounters the rear end of forward lever C it 115 will be unable to depress the latter for the reason that the latch is released, the magnet M being deenergized. The backing train will not of course be able to reach the lever D' and put on the ground 67 to energize the 120 magnet M inasmuch as before it reaches this lever D' it must first pass over the rear end of lever C. For the sake of clearness the circuit which controls the magnet M' of the forward 125 lever C may be traced as follows: from line 130

L by way of conductor 64 windings of magnet M, conductor 69, branch conductor 70 to the rear contacts of rear lever D (now open) to conductor 71, thence by way of contacts of lever E' to ground at 73.

While we have herein shown an embodiment of our invention it is of course apparent that it could be changed in various ways without in any manner departing from the spirit of the invention.

We claim as our invention:

1. In a railway block system, the combination with a suitable support of a contact lever pivoted between its ends upon said sup-

15 port and provided with two oppositely inclined track surfaces whereby the lever is oscillated and its position changed twice by the traverse thereover of a traversing member carried by a train.

20 2. In a railway block system, the combination with a suitable support of a contact lever pivoted between its ends upon said support and provided with two oppositely inclined track surfaces whereby the lever is oscillated and its position changed twice by the traverse thereover of a traversing member carried by a train, and circuit controlling devices controlled by said lever.

3. In a block system, a contact controlling lever pivoted between its ends and provided with two oppositely inclined track surfaces whereby its position is changed twice by the traverse thereover of a traversing member carried by a train, and locking mechanism associated with said lever for locking it in one of its positions.

4. In a block system, a contact controlling lever pivoted between its ends and provided with two oppositely inclined track surfaces 40 whereby the lever will be oscillated and its position changed twice by the traverse thereover of a traversing member carried by a train, and means for locking said contact lever against oscillation in either one of its two positions.

5. In a block system, a blocking lever pivotally mounted between its ends and adapted to be oscillated twice by the traverse thereover of a traversing member carried by a train, a locking mechanism associated with one end of said lever for locking that end of the lever against depression, a magnet controlling said locking mechanism, and an electric circuit connected with a source 55 of energy including the windings of said magnet.

6. In a block system, a blocking lever pivotally mounted between its ends and adapted to be oscillated twice by the traverse 60 thereover of a traversing member carried by a train, locking mechanism associated with each end of said lever and adapted to lock the latter in either of its two positions, and a magnet associated with each locking 65 mechanism and controlling the latter.

7. In a block system, a blocking lever provided with two oppositely inclined track surfaces and pivoted between its ends, two sets of self-acting locking mechanisms associated with said lever and adapted to lock 70 the latter in either of its two positions, a pair of magnets respectively associated with the two locking mechanisms and adapted to unlock the latter when energized, electric circuit connections including said magnets, 75 and means actuated by the traverse of a train and located at a distance from said locking lever for controlling said circuit connections.

8. In a block system, the combination 80 with a length of track, of a set of levers at each end of said length, each set comprising a blocking lever pivoted between its ends, locking mechanism for locking the lever in either of its two positions, magnets for controlling said locking mechanism, and a second lever pivotally supported, adapted to be actuated by the traverse thereover of a traversing member carried by a train, and electrical contact devices controlled by said 85 second lever, of a source of electric current, and circuit connections including said magnets and the contacts controlled by said contact levers whereby the contact levers control the blocking levers electrically. 95

9. In a block system, the combination with a length of track or block, of a blocking lever pivoted between its ends and having two oppositely inclined track surfaces whereby it is oscillated twice during the traverse 100 thereover of an actuating member carried by a train, electrically controlled locking mechanism associated with said lever for locking it in one of its positions, a self returning contact-controlling lever pivotally mounted 105 and adapted to be oscillated by the traverse thereover of a member carried by a train, electro-magnetic means controlling the restoration of said contact lever to normal, a circuit for said latter means extending to 110 the remote end of the block, train actuated contact devices for controlling the latter circuit at said remote end of the block, and a circuit for actuating the locking mechanism of the blocking lever, controlled by contacts 115 actuated by said contact lever, whereby the return of the latter to normal effects the unlocking of the blocking lever.

10. In a block system, the combination with a length of track or block, of a blocking 120 lever pivoted between its ends and having two oppositely inclined track surfaces whereby it is oscillated twice during the traverse thereover of an actuating member carried by a train, automatically acting, electrically retracted locking mechanism associated with said blocking lever for locking it in one of its positions, a self-returning contact controlling lever removably mounted and adapted to be actuated by the traverse thereover 125 130

of a member carried by a train, automatically engaging electrically releasable retaining mechanism controlling the restoration of said contact lever to normal, a circuit for 5 said retaining mechanism extending to the remote end of the block, train actuated contact devices for controlling the latter circuit at said remote end of the block, and a circuit for actuating the locking mechanism of the 10 blocking lever, controlled by contacts actuated by said contact lever, whereby the traverse of a train over the contact lever places the blocking lever in blocking condition and the return of the contact lever to normal 15 effects the unlocking of the blocking lever.

11. In a block system, the combination with a length of track or block, of a blocking lever pivoted between its ends and having two oppositely inclined track surfaces where- 20 by it is oscillated twice during the traverse thereover of an actuating member carried by a train automatically engaging electrically retracted locking mechanism associated with said lever for locking it in one of its po- 25 sitions, a source of electrical energy, normally grounded at one side, a circuit ex- tending therefrom through the magnet of said locking mechanism and to ground through two branches respectively controlled 30 by levers located, one adjacent to the locking lever and the other at the remote end of the block, a self-returning electrically-re- 35 leasable contact lever controlling the ground- ed branch of said circuit adjacent to the blocking lever, a circuit controlling the re- 40 leasing mechanism of said contact lever and extending to the remote end of the block, and a train-actuated contact lever located at said remote end of the block and control- ling said releasing mechanism.

12. In a block system, the combination with a length of track or block, of a blocking lever pivoted between its ends and having two oppositely inclined track surfaces where- 45 by it is oscillated twice during the traverse thereover of an actuating member carried by a train, automatically engaging locking mechanism associated with each end of said blocking lever, mechanisms arranged to re- 50 lease each of said locking mechanisms, suitable circuit connections and means located at the same end of the block with the blocking lever for temporarily energizing the magnet controlling one of said locking mech- 55 anisms, and suitable circuit connections and means located at the remote end of the block for closing a temporarily open circuit through the magnet controlling the other locking mechanism.

60 13. In a railway system, the combination with a suitable support, of a lever pivoted between its ends upon said support and

adapted to be oscillated twice by the traverse thereover of a traversing member carried by a train.

14. In a block system, a contact controlling lever pivoted between its ends and pro- vided with track surfaces whereby its posi- 70 tion is changed twice by the traverse thereover of a traversing member carried by a train, and locking mechanism associated with said lever for locking it in one of its posi- tions.

15. In a railway system, the combination with a lever pivotally mounted between its 75 ends, and adapted to be oscillated twice by the traverse thereover of a traversing mem- ber carried by a train, and means for yield- ably holding said lever in the position in which it is left after the traverse thereover 80 of said traversing member.

16. In a railway block system, the combi- nation with a length of track, of a blocking lever pivotally mounted between its ends adjacent to said track, locking mechanism 85 for limiting the depression of one end of said lever and train carried mechanism adapted to oscillate said lever into engagement with said locking mechanism.

17. In a railway system, the combination 90 with a track and a blocking lever, of one or more train actuated contact controlling le- vers and a train carried lever adapted to be actuated by said blocking lever, and adapted to actuate said contact controlling levers. 95

18. In a railway block system, the combi- nation with the air-brake pipe of a train, of a lever pivotally mounted between its ends and adapted to close the outlet of said pipe, and a second lever pivotally mounted be- 100 tween its ends and adapted to lock said first lever in closed position, a traversing mem- ber carried by said second lever, means for normally holding said traversing member in depressed position, and blocking mechanism 105 associated with the track for lifting said traversing member, thereby tripping the locking lever and releasing the first lever to vent the pipe.

19. In a railway block system, the combi- nation with the air brake pipe of a train, of a pivotally mounted lever adapted to close the outlet of said pipe, a spring actuated lever adapted to lock said first lever in closed position, and blocking mechanism asso- 110 ciated with the track for automatically tripping said locking lever to release the first lever and vent said pipe.
